UNITED STATES PATENT OFFICE.

GEORGE W. VANDEVENDER, OF MILL CREEK, WEST VIRGINIA, ASSIGNOR OF ONE-HALF TO ADAM S. VANDEVENDER, OF MINGO, WEST VIRGINIA.

FOLDING COOP.

Application filed May 2, 1921. Serial No. 466,187.

To all whom it may concern:

Be it known that I, GEORGE W. VANDEVENDER, a citizen of the United States, residing at Mill Creek, in the county of Randolph, State of West Virginia, have invented certain new and useful Improvements in Folding Coops; and I do hereby declare the following to be a full, clear, and exact description of the invention, such as will enable others skilled in the art to which it appertains to make and use the same.

This invention relates to new and useful improvements in coops and particularly to folding coops.

One object of the invention is to provide a folding coop having novel and improved interlocking means between the sides and ends, by means of which said sides and ends will be maintained against inward folding movement when the cover or top member is removed.

Another object is to provide a coop of this character wherein the folding sides are formed with means which engage with the base or bottom to prevent outward movement and which means is used to hold bolts for maintaining the coop in folded position.

A further object is to provide a coop of this character wherein the top has means for engagement with the sides and arranged for the reception of bolts for maintaining the top and other parts in set up position, said bolt receiving means of the top also serving to engage with the folded ends, to prevent loss of the top when the coop is folded.

Other objects and advantages will be apparent from the following description when taken in connection with the accompanying drawing.

40 In the drawing:

Figure 1 is a side elevation of the coop in set up position.

Figure 2 is an end view of the coop.

45 Figure 3 is a top plan view of the coop in set up position, one of the corners, at one end, being broken away to show the interlocking of the sides and ends, and the other end corner being broken away in a plane a short distance above the base.

50 Figure 4 is a top plan view of the coop in partly folded position, the ends being folded down onto the base, with the cover resting thereon, and with the sides in upstanding position.

Figure 5 is a top plan view of the coop in 55 completely folded position.

Figure 6 is an end view of the coop in completely folded position.

Referring particularly to the accompanying drawings, there is shown a base which 60 includes the longitudinal side bars 10, undercut, or rabbeted, at 11, to receive the ends of the transverse end bars 12, which are secured to said side bars, and the bottom board 13 secured to the lower faces of the side bars 65 10, inwardly of the end bars 12.

The sides 14, and the ends 15, of the coop, are preferably formed from heavy wire and include the frames 14' and 15', to which are secured, respectively, the vertical wires 14^a, 70 15^a, and the longitudinal wires 14^b and 15^b. Extending vertically between the top and bottom wires of the frame 14', in parallel relation to each vertical end wire, and in close proximity thereto, is a wire 16. The top 75 wire of each of the end frames 15' has each of its ends extending a short distance beyond the end of the frame, as shown at 17, and is disposed between the upper ends of the vertical end wires of the frames 14' and the vertical wires 16. By this construction the sides 14 are prevented from movement inwardly toward folded position, while the ends 15 are prevented from any movement 80 inwardly toward folded position. 85

The lower horizontal wire of each of the frames 14' is formed with the outwardly extending loops 18, which rest on the upper faces of the bars 10, when the said sides are in upright position, to prevent outward movement of the sides. These horizontal wires of the frames 14' are pivotally mounted 90 on the bars 10 by means of the staples 19. Similarly, the lower horizontal wires of the end frames 15' are pivotally mounted on the end bars 12, by means of the staples 20, and each of the said wires is formed with outwardly extending loops 21, similar to the loops 18, and resting on the upper faces of the bars 12, to prevent outward pivotal movement of the ends 15. The interlocking engagement of the sides and ends, effectively maintain the said sides and ends in vertical position, while the loops 18 and 21 prevent the disengagement of the sides and ends. The disengagement is accomplished by springing the ends of the sides 14 away from the ends of the ends 15, so that the projec- 100 105

tions 17 will be displaced from between the ends wires of the frames and the vertical wires 16. The ends 15 may then be folded down onto the board 13, between the bars 10, in which position the loops 21 will stand vertically, as seen in the views showing the folded position of the coop. As seen in the completely folded view, Figure 5, the loops 18, of the sides 14, stand vertically, the purpose of which will appear later herein.

The top or cover of the coop includes the tortuously bent wire 22 which has the longitudinal side wires 23. Each of these wires 23 is formed with the depending loops 24, which, when the top is in place on the upper edges of the sides 14 and ends 15, are disposed outwardly of the said sides, and inwardly of the upper ends of the vertical wires 16, for the reception of the long bolts 25, which bolts extend across the coop. Each bolt 25 has a head on one end which bears against the adjacent loop, and a nut 26 on its other end, which bears against the loop adjacent thereto, so that the sides 23 are drawn firmly inwardly into close contact with the ends, to maintain the projections 17 in proper engaged position. Transverse wires 27 are secured across the tortuous wire of the top, and terminate at the side wires 23. An access opening 28 is formed in the center of the top, and is closed by a door 29. A short wire 27' extends across the tortuous wire, from one of the side wires 23, to the adjacent side of the opening 28, and a short distance into said opening. The door has an eye 30 formed in its side wire 31 for the reception of the projecting end of the wire 27', while the projecting end 29' of the said side wire 31 of the door, rests on the adjacent wire 27 of the opening. The other end of the wire 31 is looped around the adjacent wire 27 and under the next outer wire 27, as seen at 32, to exert an upward pressure on the door to cause the eye 30 to bind on the projecting end of the short wire 27', with

the result that the door will be firmly held in closed position. This door is pivotally connected to the other end wire of the opening 28, as clearly seen in the plan view, Figure 3.

Attention is particularly called to the fact that when the ends 15 are folded down onto the base, and the top placed thereon, the opposite ends of certain of the eight portions of the tortuous wire 22 embrace the then upstanding loops 21 of the ends 15 of the coop, with the result that the said top is effectively prevented from sliding longitudinally. In this position the top lies between the side and end bars 10 and 12 of the base. After the top is properly positioned on the folded ends 15, the sides 14 are folded down onto the top. The loops 18 of the sides then stand vertically, and when the bolts 25 are slipped through said loops, across the folded sides, the folded parts are firmly held against any movement, and the coop is in a compact condition, so that it can be easily handled and occupy a small space.

What is claimed is:

A folding coop comprising a base, side and end walls hinged to the base and foldable thereon, each end of each side wall having vertical parallel bars, a removable cover having loops adjacent its corners depending below the upper portions of the side walls to receive fastening devices therethrough, and longitudinally extending bars on the upper ends of the end walls having their opposite ends projecting beyond the ends of the walls and resiliently held between the upper ends of the parallel bars of the side walls.

In testimony whereof, I affix my signature, in the presence of two witnesses.

GEORGE W. VANDEVENDER.
